MIXING FAUCET

Vance V. Elkins, Cheyney, Pa., assignor to The
 Charles E. Hires Company, Philadelphia, Pa.,
 a corporation of Delaware

Application February 27, 1946, Serial No. 650,461

15 Claims. (Cl. 222—133)

1

This invention relates to new and useful improvements in mixing faucets and more particularly to mixing faucets for dispensing carbonated and like beverages composed, for example, of a mixture of a suitably flavored syrup and carbonated or charged water.

One object of the present invention is to provide a mixing faucet of the stated character which embodies novel features of construction and arrangement operable to effect the mixture of a syrup and charged water in suitable proportions.

Another object of the invention is to provide a mixing faucet of the type described wherein a small volume of charged water entering the faucet under high pressure is caused to be reduced in pressure in successive stages therein so that there is discharged from the faucet a large volume of charged water at a minimum pressure with a minimum loss of carbonation.

Another object of the invention is to provide a mixing faucet of the character set forth which is operable to discharge a predetermined quantity of syrup therefrom each time that the faucet is actuated to the "on" position thereof.

A further object of the invention is to provide a novel and improved mixing faucet having the features and characteristics set forth which is of relatively simplified, compact construction and entirely foolproof and efficient in operation and use.

These and other objects of the invention and the various features and details of the construction and operation thereof are hereinafter fully set forth and described with reference to the accompanying drawing, in which:

Fig. 1 is an elevational view of a mixing faucet made according to the present invention.

Fig. 2 is a sectional view taken on line 2—2, Fig. 1.

Fig. 3 is a sectional view taken on line 3—3, Fig. 2.

Fig. 4 is a sectional view taken on line 4—4, Fig. 3.

Fig. 5 is a sectional view taken on line 5—5, Fig. 3; and

Fig. 6 is a perspective view of one element of the mixing faucet.

Referring now more particularly to the drawing, a mixing faucet made according to the present invention comprises essentially a casing structure 1 and nozzle structure 2. The casing 1 includes a hollow cylindrical wall member 3 which is closed at its upper end by a top plate 4 and its lower end by a bottom plate 5, the said wall 55

2

member 3 and top and bottom plates 4 and 5 being secured together in any conventional manner to provide internally thereof a fluid-tight chamber 6.

5 As best shown in Figs. 2 and 3 of the drawing, the casing top plate 4 is provided, for example, with a plurality of equally spaced openings 7 therethrough. On the other hand, the casing bottom plate 5 is provided with a port or passage 8 which extends vertically therethrough and has its axis eccentrically disposed laterally with respect to the axis of the casing 1. A pipe 9 of selected height may be provided to extend upwardly within the chamber 6 from the passage 8 for the purpose hereinafter described. In addition to the port 8, the bottom plate 5 also is provided with a second port or passage 10 which extends laterally inward from the side of said plate and then extends vertically downward therethrough as shown. It is to be noted that in the illustrated embodiment of the invention the flow area through the port or passage 10 is substantially smaller than the flow area through the port or passage 8.

15 Extending coaxially through the casing 1 and rotatably journaled in the top and bottom plates 4 and 5 thereof, respectively, is a spindle 11 which is provided in its upper end portion with a port or passage 12 that extends axially downward a predetermined distance from the upper end face of the spindle and then radially so that it opens into the casing chamber 6 adjacent the top thereof as shown, said passage 12 serving as a vent for the chamber 6.

20 25 Keyed to the spindle 11, for example by means of a pin 13, and overlying the upper surface of the top plate 4, is a valve plate 14 which is constructed and arranged as hereinafter described to open and close the openings 7 in said top plate 4 depending upon the rotational position of the spindle 11. The valve plate 14 is urged against the surface of the top plate 4 by means of a spring or the like 15 which is fixed to the spindle 11 as indicated at 16.

30 35 As previously stated, in addition to the casing 1, the mixing faucet of the present invention comprises a nozzle structure 2. This nozzle structure 2 is mounted upon and rotationally carried by the lower end of the spindle 11 at the underside of the said casing 1 in bearing engagement therewith. The nozzle structure 2 comprises an annular upper plate 17 composed, for example, of hard rubber or the like, which

40 45 provides an adequate bearing surface for rota-

tional movement of the nozzle 2 relative to the casing 1.

Underlying the plate 17 is an annular main nozzle body 18 and beneath this there is an annular base member 19. The bearing plate 17, body 18 and base plate 19 are secured in the described relation upon the lower end of the spindle 11 by means of said base plate 19 which is threaded onto the spindle lower end as indicated at 20. The nozzle body 18 is locked against rotation with respect to the spindle 11 by providing inter-cooperating flat portions 21 on said members, respectively, for example as shown in Fig. 5 of the drawings. Secured, for example, by means of threads 22 to the lower end of the base plate 19, is a mixing and discharge tip 23 which may be of transparent material so that the mixture and flow of fluids therethrough may be visually observed.

The bearing plate 17 of the nozzle structure 2 is provided with a port 24 therein arranged for movement into and out of registry with the port or passage 8 in the bottom casing plate 5 as hereinafter described. Similarly, the nozzle body 18 is provided with a port or passage 25 therein which is disposed in alignment with the port 24 of the plate 17 and, at its lower end, is in communication with a chamber 26 likewise provided in the body 18. The port 25 and the adjacent portion of the port 24 preferably have fitted therein a sleeve or lining 27. The body chamber 26 extends laterally inward and opens into the inner surface of the annular body 18 where it communicates with the inner end of a passage 28 that extends radially inward of the spindle 11 and then extends axially therethrough with its other end opening in the lower end face of said spindle interiorly of the tip 23.

In addition, there is provided in the bearing plate 17 a port 29 arranged for movement into and out of registry with the passage 10 in the casing bottom plate 5, and this port 29 communicates with a port 30 that extends through the nozzle body 18. This port 30 in the body 18 in turn communicates with an annular chamber 31 provided in the upper surface of the nozzle base plate 19, and the latter is further provided with one or more ports 32 which lead from the chamber 31 and open outwardly of the underside of said plate 19 into the tip 23. Washers 33 and 34 of suitable material are provided between the base plate 19 and nozzle body 18 to prevent fluid leakage from the chamber 31 outwardly between said body and plate and inwardly along the spindle 11. Secured upon a shoulder 35 provided in the base plate 19 is an annular disk element 36 which extends substantially horizontally within the chamber 31 and has its outer edge spaced inwardly from the washer 33 to permit the passage of fluid therebetween, the said disk 36 functioning as a diffuser plate in the manner hereinafter described.

It is to be noted that the upper portion of the port 30 is counterbored as indicated at 37 to the same diameter as the bearing plate port 29 to receive therein a jet element 38. This jet element 38 comprises an upper tubular portion 39 which seats on the shoulder provided by the counterbore 37 and extends upwardly therefrom at least partially through the bearing plate port 29 as shown. Extending coaxially from the portion 39 of the jet 38 is a tip portion 40 of reduced diameter which extends into the port 30 and it is to be noted that the diameter of this

tip portion 40 is less than that of the surrounding portion of said port 30 to provide clearance therebetween for the passage of a fluid. The bottom end of the tip portion 40 is closed and fluid passing downwardly therethrough is discharged outwardly through openings 41 in the tip side wall (see Fig. 6) having a combined area greater than the flow area through the jet 38 and passage 10. In addition to performing its special function hereinafter described, the jet 38 together with the previously mentioned sleeve 27 provide an effective interlock between the nozzle body 18 and bearing plate 17 thereby securing the latter against rotation relative to the body 18 and the spindle 11.

The nozzle structure 2 together with the spindle 11 is adapted to be rotated relative to the casing structure 1 between "on" and "off" positions by means of a suitable handle 42 secured, for example, to the nozzle body member 18, and suitable stops 43 and 44 preferably are provided and disposed in the path of movement of the handle 42 to positively limit travel thereof between said positions. These stops 43 and 44 may be provided at the underside of a plate or bracket 45 secured to the underside of the casing bottom plate 5 as shown.

In this connection, it is to be noted with reference to Figs. 4 and 5 of the drawings, that the passages 8 and 10 provided in the casing bottom plate 5, and the ports 24 and 29 in the nozzle bearing plate 17 are positioned circumferentially with respect to one another so that when the nozzle 2 is in the "on" position shown, the said bearing plate ports 24 and 29 register with the casing passages 8 and 10, respectively, and that when the nozzle 2 is in the "off" position the said bearing plate ports 24 and 29 are out of registry with said casing passages 8 and 10 thereby preventing the flow of fluids through the nozzle 2 and outwardly of its tip 23. In addition, it is to be noted that the relationship of these passages 8 and 10 and ports 24 and 29 preferably is such that, when the nozzle 2 is actuated to "on" position by the handle 42, the port 29 will establish communication with the casing passage 10 just prior to the establishment of communication between the casing passage 8 and nozzle port 24. The valve plate 14 which is carried by the spindle 11 and overlies the casing top plate 4 is constructed and arranged with respect to said spindle and casing plate so that when the spindle 11 and nozzle structure 2 are in the "off" position of the nozzle, the openings 7 in the casing top plate 4 will be open, and in the "on" position of the nozzle will be closed.

In operation of a device made according to the present invention, and assuming that it is to be employed to mix and dispense a carbonated beverage comprising, for example, a mixture in suitable proportions of a flavored syrup and a carbonated or charged water, the device may have its casing portion 1 secured in the manner illustrated in the bottom portion 46 of a suitable vessel which contains a supply of the desired syrup, a suitable fluid-tight joint 47 being provided to prevent leakage of the syrup outwardly between the vessel and casing structure 1, and a supply of carbonated or charged water under high pressure may be supplied to the passage 10 in the casing bottom plate 5 by means of a suitable tube or pipe 48.

With the nozzle in the "off" position thereof, the valve plate 14 will be open with respect to

the top plate openings 7 so that syrup from the vessel will flow through said openings 7 into the chamber 6 thereby filling the latter. If now the nozzle 2 is actuated to the "on" position thereof, the valve plate 14 will close the openings 7 in the top plate 4, and the ports 24 and 29 will be moved into registry with the bottom plate passages 8 and 10, respectively, the arrangement being such that the port 29 moves into communication with the passage 10 just in advance of 10 movement of the port 24 into communication with the passage 8.

As the port 29 moves into registry with the orifice or passage 10 a small volume of charged water supplied under high pressure by the pipe 15 48 enters the jet element 38 wherein it is deflected and discharged through openings 41 which have a combined area greater than the flow area through the jet 38 and passage 10 and thereby effect a first reduction in pressure of the charged water. The resulting streams of charged water are further deflected downwardly into port 30 which is of still greater area and effects another reduction in pressure of the water. From the port 30 the water is directed against the diffuser plate or disk 36 which again changes the direction of flow and causes the water to flow downwardly over the peripheral edge of said plate 36 into the larger space afforded by the annular chamber 31 thereby effecting a further reduction in pressure of the water. From the chamber 31 the water discharges outwardly through the series of ports 32 resulting in still a further reduction in pressure of the water, and finally strikes the tapered side walls of the discharge tip 23 with a minimum of deflection causing the several streams of water to be blended or combined into one low pressure stream of large volume which is discharged therefrom. By reducing the pressure of the charged water in this manner by successive stages within the faucet where it is confined, loss of carbonation or carbon dioxide gas in the charged water is reduced to a minimum as compared with the loss of carbonation which occurs when the pressure of charged water is reduced in a single stage and simultaneously discharged into the open atmosphere.

While the foregoing is taking place, syrup from the casing chamber 6 flows downwardly through the pipe 9 and passage 8 through ports 24 and 25 to the chamber 23 and thence through the spindle passage 22 to the discharge tip 23. Since the openings 7 are closed to prevent the flow of additional syrup into the casing chamber 6, only that amount of syrup within said chamber above the level of the top of the pipe 9 will flow from the chamber through the nozzle structure as described, and it will be apparent that by providing pipes 9 of different height the quantity of syrup discharged from the device each time that it is opened may be predeterminedly selected as desired or required.

As previously described, the charged water is caused to be discharged from the nozzle just slightly in advance of the syrup, and this arrangement is provided to prevent any syrup from being discharged into the bottom of a glass or other receptacle held beneath the nozzle and collecting there before mixing with the charged water. When the glass or receptacle is filled the nozzle is actuated to the "off" position thereof whereupon the discharge of charged water and syrup is stopped and the openings 7 in the casing 75

top plate 4 are opened to cause the syrup in the vessel to flow into and fill the casing member 6.

From the foregoing description it will be apparent that the present invention provides a novel improved mixing faucet which is constructed and arranged to effect the mixture of two fluids in suitable proportions. The invention also provides a mixing faucet of the type described where-in a small volume of charged water entering the faucet under high pressure is caused to be reduced in pressure in successive stages within said faucet so that there is discharged therefrom a large volume of charged water at a minimum pressure with a minimum loss of carbonation. In addition, the invention provides a mixing faucet of the character set forth which is operable to discharge a predetermined quantity of a fluid each time that the device is actuated to the "on" position thereof. Furthermore, the invention provides a mixing faucet having the features and characteristics set forth which is of relatively simplified compact construction and entirely fool-proof and efficient in operation and use.

It will be observed, of course, that the mixing faucet of the present invention is not limited to the particular uses herein specified but may be employed generally in all cases where it is desired to effect the mixture and discharge of a plurality of fluids, and while a particular embodiment of the invention has been illustrated and described herein, the invention is not to be limited to such disclosure and changes and modifications may be made therein and thereto within the scope of the claims.

35 I claim:

1. A mixing faucet comprising a casing defining a fluid chamber therein and having opening outwardly through the bottom thereof a first fluid passage constituting an outlet from said chamber and a second fluid passage leading exteriorly of the casing, and a nozzle rotatably mounted in bearing engagement with the bottom of said casing and actuatable between on and off positions, said nozzle having therein a first fluid discharge passage arranged in the on position of the nozzle to register with said first passage of the casing, and a second fluid discharge passage arranged in said on position of the nozzle to register with said second passage of the casing.

2. A mixing faucet comprising a casing defining a fluid chamber therein and having opening outwardly through the bottom thereof a first fluid passage constituting an outlet from said chamber and a second fluid passage leading exteriorly of the casing, and a nozzle rotatably mounted in bearing engagement with the bottom of said casing and movable between on and off positions, said nozzle having therein a first fluid discharge passage arranged in the on position of the nozzle to register with said first passage of the casing and a second fluid discharge passage arranged in said on position of the nozzle to register with said second passage of the casing, and said first and second fluid discharge passages in the nozzle being arranged therein with respect to each other so that communication from said second casing passage to said second nozzle passage is established in advance of communication between said first passages of the casing and nozzle.

3. A mixing faucet comprising a casing defining a fluid chamber therein and having an inlet opening thereto, said casing also having opening outwardly through the bottom thereof a first fluid passage constituting an outlet from said chamber and a second fluid passage leading exteriorly

of the casing, a nozzle rotatably mounted in bearing engagement with the bottom of said casing and movable between on and off positions, said nozzle having therein a first fluid discharge passage arranged in the on position of the nozzle to register with said first passage and a second fluid discharge passage arranged in said on position of the nozzle to register with said second passage of the casing, a member cooperatively arranged with respect to the inlet opening to the chamber operable to close and open the same, and means interconnecting said nozzle and said member operable to actuate the latter into closing relation with the chamber inlet opening when the nozzle is in the on position and into open relation with said chamber inlet when the nozzle is in the off position.

4. A mixing faucet comprising a casing defining a fluid chamber therein and having an inlet opening to said chamber, said casing also having opening outwardly through the bottom thereof a first fluid passage constituting an outlet from said chamber and a second fluid passage leading exteriorly of the casing, a nozzle rotationally mounted in bearing engagement with the bottom of said casing and movable between on and off positions, said nozzle having therein a first fluid discharge passage arranged in the on position of the nozzle to register with said first passage of the casing and a second fluid discharge passage arranged in said on position of the nozzle to register with said second passage of the casing, said first and second fluid discharge passages in the nozzle being arranged therein with respect to each other so that communication from said second casing passage to said second nozzle passage is established in advance of communication between said first passages of the casing and nozzle, a member cooperatively arranged with respect to the inlet opening to the chamber to close and open the same, and means interconnecting said nozzle and said member operable to actuate the latter into closing relation with the chamber inlet opening when the nozzle is in the on position and into open relation with said chamber inlet when the nozzle is in the off position.

5. A mixing faucet comprising a casing defining a fluid chamber therein and having opening outwardly through the bottom thereof a first fluid passage constituting an outlet from said chamber and a second fluid passage leading exteriorly of the casing, a nozzle rotationally mounted in bearing engagement with the bottom of said casing and movable between on and off positions, said nozzle having therein a first fluid discharge passage arranged in the on position of the nozzle to register with said first passage of the casing and a second fluid discharge passage arranged in said on position of the nozzle to register with said second passage of the casing, and means in said nozzle second passage operable to effect successive reductions in pressure of the fluid discharged therethrough.

6. A mixing faucet comprising a casing defining a fluid chamber therein and having opening outwardly through the bottom thereof a first fluid passage constituting an outlet from said chamber and a second fluid passage leading exteriorly of the casing, a nozzle rotationally mounted in bearing engagement with the bottom of said casing and rotatable between on and off positions, said nozzle having therein a first fluid discharge passage arranged in the on position of the nozzle to register with said first passage of the casing and a second fluid dis-

charge passage arranged in said on position of the nozzle to register with said second passage of the casing, said first and second fluid discharge passages in the nozzle being arranged therein with respect to each other so that communication from said second casing passage to said second nozzle passage is established in advance of communication between said first passages of the casing and nozzle, and means in said nozzle second passage operable to effect successive reductions in pressure of the fluid discharged therethrough.

7. A mixing faucet comprising a casing defining a fluid chamber therein and having an inlet opening to said chamber, said casing also having opening outwardly through the bottom thereof a first fluid passage constituting an outlet from said chamber and a second fluid passage leading exteriorly of the casing, a nozzle rotationally mounted in bearing engagement with the bottom of said casing and movable between on and off positions, said nozzle having therein a first fluid discharge passage arranged in the on position of the nozzle to register with said first passage of the casing and a second fluid discharge passage arranged in said on position of the nozzle to register with said second passage of the casing, means in said nozzle second passage operable to effect successive reductions in pressure of the fluid discharged therethrough, a member cooperatively arranged with respect to said inlet opening to the chamber to open and close the same, and means interconnecting said nozzle and said member operable to actuate the latter into closing relation with the chamber inlet opening when the nozzle is in the on position and into open relation with said chamber inlet when the nozzle is in the off position.

8. A mixing faucet comprising a casing defining a fluid chamber therein and having an inlet opening to said chamber, said casing also having opening outwardly through the bottom thereof a first fluid passage constituting an outlet from said chamber and a second fluid passage leading exteriorly of the casing, a nozzle rotationally mounted in bearing engagement with the bottom of said casing and rotatable between on and off positions, said nozzle having therein a first fluid discharge passage arranged in the on position of the nozzle to register with said first passage of the casing and a second fluid discharge passage arranged in said on position of the nozzle to register with said second passage of the casing, said first and second fluid discharge passages in the nozzle being arranged therein with respect to each other so that communication from said second casing passage to said second nozzle passage is established in advance of communication between said first passages of the casing and nozzle, means in said nozzle second passage operable to effect successive reductions in pressure of the fluid discharged therethrough, a member cooperatively arranged with respect to said inlet opening to the chamber to close and open the same, and means interconnecting said nozzle and said member operable to actuate the latter into closing relation with the chamber inlet opening when the nozzle is in the on position and into open relation with said chamber inlet when the nozzle is in the off position.

9. A mixing faucet comprising a casing defining a fluid chamber therein and having opening outwardly through the bottom thereof a first

fluid passage constituting an outlet from said chamber and a second fluid passage leading exteriorly of the casing, a nozzle rotationally mounted in bearing engagement with the bottom of said casing and rotatable between on and off positions, said nozzle having therein a first fluid discharge passage arranged in the on position of the nozzle to register with said first passage of the casing and a second fluid discharge passage arranged in said on position of the nozzle to register with said second passage of the casing, and means in said nozzle second passage operable to effect successive reductions in pressure of the fluid discharged therethrough including a jet and a diffusion plate.

10. A mixing faucet comprising a casing defining a fluid chamber therein and having opening outwardly through the bottom thereof a first fluid passage constituting an outlet from said chamber and a second fluid passage leading exteriorly of the casing, a nozzle rotationally mounted in bearing engagement with the bottom of said casing and rotatable between on and off positions, said nozzle having therein a first fluid discharge passage arranged in the on position of the nozzle to register with said first passage of the casing and a second fluid discharge passage arranged in said on position of the nozzle to register with said second passage of the casing, said first and second fluid discharge passages in the nozzle being arranged therein with respect to each other so that communication from said second casing passage to said second nozzle passage is established in advance of communication between said first passages of the casing and nozzle, and means in said nozzle second passage operable to effect successive reductions in pressure of the fluid discharged therethrough including a jet and a diffusion plate.

11. A mixing faucet comprising a casing defining a fluid chamber therein and having an inlet opening to said chamber, said casing also having opening outwardly through the bottom thereof a first fluid passage constituting an outlet from said chamber and a second fluid passage leading exteriorly of the casing, a nozzle rotationally mounted in bearing engagement with the bottom of said casing and rotatable between on and off positions, said nozzle having therein a first fluid discharge passage arranged in the on position of the nozzle to register with said first passage of the casing and a second fluid discharge passage arranged in said on position of the nozzle to register with said second passage of the casing, means in said nozzle second passage operable to effect successive reductions in pressure of the fluid discharged therethrough including a jet and a diffusion plate, a member cooperatively arranged with respect to said inlet opening to the chamber to close and open the same, and means interconnecting said nozzle and said member operable to actuate the latter into closing relation with the chamber inlet opening when the nozzle is in the on position and into open relation with said chamber inlet when the nozzle is in the off position.

12. A mixing faucet comprising a casing defining a fluid chamber therein and having an inlet opening to said chamber, said casing also having opening outwardly through the bottom thereof a first fluid passage constituting an outlet from said chamber and a second fluid passage leading exteriorly of the casing, a nozzle rotationally mounted in bearing engagement

with the bottom of said casing and rotatable between on and off positions, said nozzle having therein a first fluid discharge passage arranged in the on position of the nozzle to register with said first passage of the casing and a second fluid discharge passage arranged in said on position of the nozzle to register with said second passage of the casing, said first and second fluid discharge passages in the nozzle being arranged therein with respect to each other so that communication from said second casing passage to said second nozzle passage is established in advance of communication between said first passages of the casing and nozzle, means in said nozzle second passage operable to effect successive reductions in pressure of the fluid discharged therethrough including a jet and a diffusion plate, a member cooperatively arranged with respect to said inlet opening to the chamber to close and open the same, and means interconnecting said nozzle and said member operable to actuate the latter into closing relation with the chamber inlet opening when the nozzle is in the on position and into open relation with said chamber inlet when the nozzle is in the off position.

13. A mixing faucet comprising a casing defining a fluid chamber therein and having an inlet opening to said chamber in the top thereof, said casing also having opening outwardly through the bottom thereof a first fluid passage constituting an outlet from said chamber and a second fluid passage leading exteriorly of the casing, a spindle rotationally mounted coaxially through said casing, a nozzle fixed on said spindle in bearing engagement with the bottom of said casing and rotatable with said spindle between on and off positions, said nozzle having therein a first fluid discharge passage arranged in the on position of the nozzle to register with said first passage of the casing and a second fluid discharge passage arranged in said on position of the nozzle to register with said second passage of the casing, means in said nozzle second passage operable to effect successive reductions in pressure of the fluid discharge therethrough, and a member carried by said spindle in engagement with the top of said casing and cooperatively arranged with respect to the inlet opening therein to close the same when said nozzle is in the on position and to open the same when the nozzle is in the off position.

14. A mixing faucet comprising a casing defining a fluid chamber therein and having an inlet opening to said chamber in the top thereof, said casing also having opening outwardly through the bottom thereof a first fluid passage constituting an outlet from said chamber and a second fluid passage leading exteriorly of the casing, a spindle rotationally mounted coaxially through said casing, a nozzle fixed on said spindle in bearing engagement with the bottom of said casing and rotatable with said spindle between on and off positions, said nozzle having therein a first fluid discharge passage arranged in the on position of the nozzle to register with said first passage of the casing and a second fluid discharge passage arranged in said on position of the nozzle to register with said second passage of the casing, said first and second fluid discharge passages in the nozzle being arranged therein with respect to each other so that communication from said second casing passage to said second nozzle passage is established in advance of communication between said first passages of the casing and nozzle, and a member

carried by said spindle in engagement with the top of said casing and cooperatively arranged with respect to the inlet opening therein to close the same when said nozzle is in the on position and to open the same when the nozzle is in the off position.

15. A mixing faucet comprising a casing, defining a fluid chamber therein and having an inlet opening to said chamber in the top thereof, said casing also having opening outwardly through the bottom thereof a first fluid passage constituting an outlet from said chamber and a second fluid passage leading exteriorly of the casing, a tube of selected length extending vertically inward of the fluid chamber from said first passage operable to limit the amount of fluid discharged from said chamber through said passage, a spindle rotationally mounted coaxially through said casing, a nozzle fixed on said spindle in bearing engagement with the bottom of said casing and rotatable with said spindle between on and off positions, said nozzle having therein a first fluid discharge passage arranged in the on position of the nozzle to register with said first passage of the casing and communication with a coaxial discharge passage in said spindle and a second fluid discharge passage arranged in said on position of the nozzle to register with

said second passage of the casing, said first and second fluid discharge passages in the nozzle being arranged therein with respect to each other so that communication from said second casing passage to said second nozzle passage is established in advance of communication between said first passages of the casing and nozzle, means in said nozzle second passage operable to effect successive reductions in pressure of the fluid discharged therethrough including a jet, and a member carried by said spindle in engagement with the top of said casing and cooperatively arranged with respect to the inlet opening therein to close the same when said nozzle is in the on position and to open the same when the nozzle is in the off position.

VANCE V. ELKINS.
